ABSTRACT: A high-voltage relay is provided in which the operating components of the relay are enclosed in a sealed envelope which may be evacuated, for example, or filled with a pressurized dielectric gas. The relay is constructed to include an elongated envelope formed of glass, or other vitreous or electrically insulating material, and which has electrical terminals extending through the envelope at the side of the envelope and at one end, so as to provide good insulation from the grounded electromagnetic actuating components at the other end of the relay, in order that the relay may be operated at high voltages.

PATENTED DEC 14 1971

HIGH-VOLTAGE RELAY

BACKGROUND OF THE INVENTION

The relay of the present invention incorporates some of the features of the heart defibrillator relay described in U.S. Pat. No. 3,250,886 which issued May 10, 1966 in the name of Victor E. De Lucia et al. Like the relay of the aforesaid patent, the relay of the present invention is constructed to operate over extended intervals of time at extremely high voltages.

BRIEF DESCRIPTION OF THE DRAWING

The single FIGURE is a side elevation of a relay constructed in accordance with the concepts and teachings of the present invention.

DETAILED DESCRIPTION OF THE ILLUSTRATED EMBODIMENT

The illustrated relay includes a first elongated tubular-shaped envelope 10 formed of glass, or other appropriate vitreous material. The relay also includes a second tubular-shaped envelope 12 which is sealed to the envelope 10 between the ends of the envelope 10, and which extends radially outwardly with respect to the envelope 10. The envelope 12 may also be formed of glass or other appropriate vitreous material, and it defines a common internal chamber with the envelope 10.

As mentioned above, the internal chamber may be evacuated, or it may be filled with a pressurized dielectric gas. A first terminal rod 14 extends through the upper end of the envelope 10 and down into the envelope in coaxial relationship therewith. The lower extremity of the first terminal rod 14 is positioned adjacent the axis of the tubular envelope 12. A second terminal rod 16 extends into the tubular envelope 12 from one end thereof, and it is supported in coaxial relationship with the tubular envelope 12.

A movable contact 18 is hinged to the terminal rod 16 in much the same manner as described in the aforesaid patent, so that an electric path is established from the terminal rod 16 to the movable contact 18. The movable contact 18 extends across the lower extremity of the terminal rod 14 for selective contact therewith, as the movable contact 18 is moved up and down, from one angular position to the other with respect to the axis of rotation of the aforesaid hinge.

An electromagnetic actuator 19 is mounted at the lower end of the envelope 10, as shown. The electromagnetic actuator may include a usual electrical energizing coil and associated magnetic core structure. The magnetic core structure extends into the interior of the envelope 10, as designated 20, and an armature 22 is hinged to the magnetic core structure 20. The armature 22 is normally spring biased to the illustrated tilted position by means, for example, of a spring 24.

A connecting rod 26 intercouples the armature 22 to the movable contact 18, so that movement of the armature 22

from one operative position to the other, as the electromagnetic actuator 18 is energized, causes the movable contact 18 to move in and out of electrical contact with the lower extremity of the rod 14. The connecting rod 26 may be composed, for example, of a first metallic rod 26a which is pivotally coupled to the movable contact 18, and a second rod 26b which is pivotally coupled to the armature 22. An intermediate rod 26c is sealed to the rods 26a and 26b. The intermediate rod 26c may be formed of glass, or other appropriate insulating material.

It will be evident from a consideration of the illustration and of the foregoing description, that the operating contacts of the relay are displaced a relatively large distance from the grounded relay actuator at the lower end of the relay, and that appropriate insulation is provided, so that the relay may be operated at high voltages. The relay also has the advantage in that it is simple and rugged in its construction, and extremely reliable in its operation.

While a particular embodiment of the invention has been shown and described, modifications may be made. It is intended in the following claims to cover all modifications which come within the spirit and scope of the invention.

What is claimed is:

1. A relay including: a first elongated tubular-shaped envelope; a second tubular-shaped envelope affixed to said first envelope intermediate the ends thereof and extending radially outwardly with respect to said first envelope, said first and second envelopes defining a common sealed internal chamber; a first terminal rod extending through one end of said first envelope and supported thereby in coaxial relationship with said first envelope; a second terminal rod extending through the end of said second envelope and supported thereby in coaxial relationship with said second envelope; a movable contact hinged to the inner end of said second terminal rod in electrically conductive relationship therewith and extending from said inner end across the lower extremity of said first terminal rod selectively to contact said extremity; an electromagnetic actuator mounted at the other end of said first tubular-shaped envelope; an armature mounted within said first envelope adjacent said actuator to be selectively moved thereby between first and second operative positions; a connecting rod coupled to said movable contact and to said armature for causing said movable contact selectively to contact said extremity of said first terminal rod as said armature is moved from one of its operative positions to the other, and which includes a magnetic core structure incorporated in said actuator and extending into the interior of said first envelope, and in which said armature is hinged to said core structure and normally spring biased to a tilted position with respect thereto.
2. The relay defined in claim 1, in which said connecting rod comprises a first metallic rod pivotally coupled to said movable contact, a second metallic rod pivotally connected to said armature, and an intermediate rod sealed to said first and second metallic rods and formed of an insulating material.
